STOP MOTION FOR KNITTING MACHINES

Joe W. Hamilton, Los Angeles, Calif., assignor of
forty-five percent to Reynolds Jennings Ham-
ilton, Los Angeles, Calif.

Application November 18, 1936, Serial No. 111,365

5 Claims. (Cl. 66—163)

The present invention relates to a stop motion mechanism particularly adapted for knitting machinery, but also designed to operate in connection with any type of textile machinery in which the machine or mechanism is to be stopped or controlled when the yarn or thread being utilized breaks or is subjected to excessive tension or becomes tangled.

In my prior applications Ser. No. 43,308, filed October 3, 1935, and Ser. No. 38,044, filed August 27, 1935, there are described mechanisms particularly designed to operate in conjunction with knitting machinery but also capable of being operated in conjunction with other machinery in which the assurance will be had of prompt stoppage of the knitting machine when the thread breaks any place between the cone and the needle bed, when a tangle occurs, or when excessive tension arises which might tend to cause breakage if the machine were allowed to continue operation.

In these applications the yarn is caused to pass over one or more pivotally mounted guide devices, which are so constructed as to release the yarn or thread when excessive tension arises. This release of the yarn or thread will in turn permit the pivotal device to swing back actuating a stop mechanism which may be mechanically or electrically controlled.

In said prior applications, the thread may be preferably tensioned by a spring or by a weight before it passes over the main guide on the pivotal element, and if desired, a pivotal guide element may be provided in association with the drag element.

It is among the objects of the present invention to design an improved stop motion mechanism of the type above described, and which although electrically controlled, will not be subjected to derangement because of the collection of lint, dirt or dust preventing proper electrical contacts and circuit closures.

Another object is to provide electrical stop motion of the type above described in which the construction will be most compact and most readily threaded at the initiation of operation or to restart the machine after a stoppage, even though the stop motion mechanism be positioned at a considerable height.

Other objects will appear during the course of the following specification.

According to one preferred construction, a single pivotal guide is provided which takes the form of a substantially horizontal finger on the end of a lever. The lever is normally lightly ten-

sioned by a weak spring or weight which is overcome by the normal tension of the yarn when properly running. When so tensioned the other end of the lever will contact with or press against or tend to move closely toward a yielding member. This member is resiliently biased as to yield only when there is excessive tension upon the yarn or thread to permit the guide to lower it sufficiently to release or discharge the yarn.

Connected to the lever and turning therewith is a movable electrical contact which cooperates with a fixed contact, said contacts being terminals of an electric circuit. In one instance the movable element moves or balances between two fixed elements. In another a spring finger constituting the fixed element rides on a cylinder constituting the movable element. The cylinder is provided with an insert of an insulated material at the position where it is normally contacted with the spring finger.

As a result the circuit will be opened when the thread or yarn is running with the proper tension over the spring finger. When, however, the guide finger is released by the yarn or is depressed by excessive tension upon the yarn, contact will be established and the circuit will be actuated which will stop the machine.

The yarn before or while passing over said pivotal guide finger preferably passes through a fixed guide and a tensioning member, said guide being of such a character as to cause the yarn to be properly directed onto the pivotal finger during feeding thereof and so as to set up a satisfactory tension upon the yarn to cause it to normally press the lever to operating position.

The yarn may also pass over another guide on its way to the needle bed of the knitting machine which guide, however, should cooperate with the stop motion in case of breakage between the needle bed and the guide with the result that the guide finger will be released to close the stop actuating circuit.

If desired, it is also possible to insert a light signal to indicate which one of the stop motions has been used to stop the machine in the proposed construction.

The above and other objects will appear more clearly from the following detailed description, which when taken in connection with the accompanying drawings, will illustrate preferred embodiments of the inventive idea.

Figure 1 is a side view of an upper structure of a knitting machine with one of the stop motion mechanisms in position thereon.

Figure 2 is a side sectional view of the stop

motion mechanism on the line 2—2 of Figure 1 upon enlarged scale.

Figure 3 is a top view upon the line 3—3 of Figure 2 with the cover of the stop motion mechanism removed.

Figure 4 is a side sectional view upon the line 4—4 of Figure 3 showing a portion of the stop motion mechanism.

Figure 5 is a side view upon the line 5—5 of Figure 2 with the cover of the mechanism removed.

Figure 6 is a fragmentary side sectional view upon the line 6—6 of Figure 7, showing the guide mechanism.

15 Figure 7 is a fragmentary side sectional view upon the line 7—7 of Figure 6.

Figure 8 is a side view of the mechanism upon the line 8—8 of Figure 1 upon a slightly enlarged scale.

20 Figures 9 to 12 illustrate an alternative embodiment in which Figure 9 is a longitudinal section through the device upon the line 9—9 of Figure 10; Figure 10 is a top view along the line 10—10 of Figure 9 with the cover of the device removed; Figure 11 is a fragmentary front view partly in section along the line 11—11 of Figure 9 and Figure 12 is a horizontal fragmentary view along the line 12—12 of Figure 9.

Referring to Figure 1, the knitting machine indicated diagrammatically at A, is provided with the usual revolving thread guide structure and reciprocating needle bed structure (not specifically shown), the thread guide structure and the reciprocating needles being supplied with yarn from the cones indicated diagrammatically somewhat out of position at B.

The cones, which encircle the structure, are carried by the column C which is part of the rotating structure.

40 The column C carries a head D which in turn supports the stop motion mechanisms E to which the present invention is particularly directed.

The yarn F passes from the supply B to the guide G into which it is readily threaded.

45 From the guide G, the yarn passes over the guide arm H. It then finally passes through the guide I to the knitting machine A.

Referring particularly to Figures 2 to 5, the stop motion mechanism is provided with a base plate 10, which may be made of aluminum die casting or some other die casting of light metal which base plate 10 is provided with a protuberance 11 which is tapped, as indicated best at 12 in Figure 5. The cover 9 is connected to the threaded post 7 by the nut 8.

55 The stop motion mechanism is connected to the rod 13 by said tapped recess 12, as best shown in Figure 5.

Extending upwardly from the plate 10 are the side plates 14 which may be made integrally, if desired, with the base plate 10.

These side plates 14 carry the pivot mounts 15, which are screwed into tapped openings in the said plates 14, as indicated at 16 in Figure 5.

65 The pivot mounts 15 are provided with the pivot points 17 and they are locked in position by the lock nuts 18.

The pivot points 17 press into and hold the shaft 19, which is provided with a series of recesses or grooves 21, 22 and 23 and a transverse slot 64.

These recesses form a series of protuberances 24, 25, 26 and 27 (see particularly Figure 5).

In the recess 23 is fixed the curved portion 28 of the arm 29 of the movable guide H. The

curved portion 28 is held in position in the groove 23 by means of the inset 33.

The arm is provided with a bend 30 adjacent its end and at its end, as best shown in Figure 2, it carries a porcelain guide sleeve element which 5 is concaved at 32 more readily to receive the yarn F.

The other end of the arm 29 is provided with a mushroom-shaped enlargement 34 (see particularly Figure 2) which contacts with the end 10 35 of the bar 36.

The shaft 37 carries the bar 36 and it is threaded throughout its length and is screwed through the side plates 14. The bar 36 is tapped where it is received upon said shaft 37.

15 The bar 36 is provided with a dependent element 38 carrying an eye 39 to which is connected the coil spring 40. The coil spring 40 at its other end is connected to the eye 41 carried on the flange 42 of the plate 43.

20 The plate 43 is provided with an extension 44, as indicated in Figure 4, which fits under a rearwardly extending leg 45 of the side frame member 14. The screw 46 forming a pivot mount for said plate 43. The plate 43 may be adjusted by 25 means of the rod 47 which is threaded through the lugs 48 and 49 (see Figure 2) and is provided with a downwardly bent portion 50 having a coiled end 51 to serve as a handle.

25 The end 52 of the rod 47 abuts the flange 42 and by turning the handle portion 50—51 it is possible to adjust the tension upon the coil spring 40.

When the arm H is slightly tensioned downwardly as the thread or yarn is fed to the knitting machine, the mushroom portion 34 of the lever 29 will contact with the end 35 of the bar 36, but when the tension is relieved from the guide H the mushroom 34 will separate from the bar 35, the bar 35 being stopped at its other end and 40 prevented from following the lever 29 by the stop screw 53. The screw is threaded through the top plate 54, which plate may be made of an insulating material and is screwed onto the side plates 14 by the screws 67.

45 The set screw 53 is locked in any desired position upon the plate by the lock nuts 55 and 56.

The lever 29 is normally tensioned toward the base plate 10 by the relatively light spring 57, which as shown in Figure 4, is connected at one end to the opening 58 in the protuberance 24. The other end of the spring 57 is hooked onto an ear 59 which is adjustably mounted at 60 on the leg 45 extending rearwardly from the wall 14.

55 The spring 57 is of relatively light tension as compared with the spring 40 so that the lever 29 may be readily depressed by the normal yarn tension to the point indicated in Figure 2. Beyond this point, however, it will be necessary for 60 substantial tension upon the yarn to be exerted to move the lever 29 in contact with the bar 36 against the force of the substantially stronger spring 40.

In the normal balancing position, as indicated 65 in Figure 2, the contact arm 61 at its embossment 62 will contact the insulating piece 63 fitted in the axial slot 64.

The upper end of the arm 61 is turned over as indicated at 65 and is screwed as indicated at 66 to the top of the plate 54, where electrical connection may be made.

70 Electrical connections are usually provided to the base 10 and the contact arm 61 so that the stop motion circuit will be established when the 75

embossment 62 rides beyond the insulating insert 63 either because of the breakage of the yarn F and release of the arm 29, or because of excessive tension on the arm 29 tending to press the mushroom 34 against the bar 36 sufficiently to substantially depress the lever 29.

By the rod 47, the screw mount 60 and the adjusting screw 53, it is possible to adjust the tension on the arm 29 and the guide H at its various 10 positions during the operation, so that during normal operation the embossment 62 will ride upon the insulation 63 opening the stop motion circuit.

To assure that the thread be guided on to the 15 sleeve 31 of the guide H in a proper fashion, the guide element G is provided, which guide element G is also so constructed as to enable ready threading of the yarn thereupon by a threading stick, as is necessary in most textile plants.

20 Referring to Figures 2 and 5 to 7, the guide G is carried on an arm 75 depending downwardly from the base plate 10, which arm has an inturned portion 76 carrying the sheet metal cover 77 (see Figure 2).

25 The arm is also provided with a further in-turned extension 78 which carries the screw 79 locked in position by the lock nut 80 (see Figure 6).

The screw carries the shank 81 of the guide disk 30 82, which guide disk 82 is provided with a recess 83 and with a bevel face 84.

The disk also carries a guide wire 86 (best shown in Figure 7) which at one end 87 fits into the 35 disk 82 and at its other end 88 turns rearwardly until it fits into the arm 78.

35 Pressing against the inside face of the disk 82 is the cup 89 which is biased by the spring 90, the tension of which is adjusted by the adjustable reaction member 91, carried on said threaded 40 shaft 79.

The guide wire 86 forms a convenient means by which the yarn F is prevented from moving out of the recess 83, as shown in Figure 7, when the 45 yarn is passing from the bobbin or cone B to the knitting machine A.

The wire 86 also guides the thread F, as shown in the lower part of Figure 2.

In operation, the yarn F is first looped over the 50 sleeve 32 and then the wire 86, it may be readily placed in the recess 83, as best shown in Figure 7.

The normal feeding tension on the yarn across the sleeve 32 will depress the arm 29 of the guide H until the mushroom 34 just barely contacts with the end 35 of the bar 36, the normal tension 55 of the yarn being sufficient to overcome the spring 57, but not to overcome the spring 40.

In this position, the circuit is broken at the insulation 63, as indicated at Figure 4.

When the thread breaks beyond the stop motion mechanism E, the lever 29 will be released 60 and the embossment 62 will ride off the insulation 63 closing the circuit between the base 10 and the arm 61, stopping the machine.

The closure of this circuit will also illuminate 65 the lamp 100, as shown in Figure 5, indicating to the worker which stop motion mechanism has been actuated.

The excessive tension will also give rise to the same effect by depressing the lever 29 against the 70 spring 40 acting on the pivotally mounted abutment bar 36.

The guide G at all times will function to feed the yarn properly upon the sleeve 32.

The guide I will receive the yarn F just before 75 it reaches the revolving structure A and it con-

sists of a spring pressed disk 110 similar to disk 89. This disk is supported on a lever 111 pivotally mounted on the arm 112. The arm 112 is weighted by the adjustable element 113.

If the yarn F breaks between the device I and 5 the machine A, the lever 111 would move up on the right causing sufficient slack to permit the guide H to elevate and close the stop circuit.

It is thus evident that the applicant has provided a convenient, inexpensive and durable 10 mechanism which will actuate under a wide variety of conditions to stop the machine.

The device shown and described in the present application will satisfactorily provide for practically every abnormal treatment imposed upon 15 the yarn. For example, it will function very satisfactorily when the tension becomes too great and it will not be necessary for the cloth to drop out before such actuation.

Moreover, it will most readily function when 20 a loose end runs out and/or when the thread breaks or separates at any appointed position.

The device of the present invention excels in the ability to stop the knitting machine without necessitating the removal of the yarn from the 25 stopping device, and this is a marked improvement over the prior art, since in most cases in the prior art the stop motion will not operate as long as the yarn stays in position. This advantage is particularly apparent in case of separation of the 30 thread at any point between the stop motion device and the needle bed.

By the utilization of the combination shown it is possible to stop the knitting machine in case of separation of the thread at any point between the 35 cone and the needle bed.

The device of the present application is particularly advantageous inasmuch as it will function to stop the knitting machine upon tangling of the thread, or when normally lodged knots 40 occur in the yarn without there occurring at any time a drop out of any considerable degree. In practically all instances where the device of the present application will effectively stop the machine, the operator of the machine will be able 45 to tie on a new thread without any damage to the cloth. The device of the present invention may be made of brass or other materials and it may be utilized on flat type or circular knitting machines utilizing 6, 12 or any other number of 50 threads.

The specific dimensions of the various springs, lever and so forth may be varied from machine to machine, and may be most satisfactorily controlled in accordance with the character and 55 strength of the yarn.

By utilization of a combination of fixed and pivoted guides as shown in the present application, it is not only possible to stop the knitting 60 machine when the yarn breaks but generally the machine will be stopped before the yarn breaks, when the tension upon the yarn becomes such as to upset the pivoted guides and permit release of the yarn. Although the pivoted members are 65 provided with adjustable springs, it may be desirable in some instances to make the springs in-adjustable. Weights if desired may be used with or in addition to springs.

In the embodiment of Figures 9 to 12 is shown 70 in alternative form of stop motion mechanism, in which similarly functioning parts are designated by the same numerals as Figures 1 to 8, however, primed.

In Figure 9, the boxlike container 10' is pro- 75

- vided with a cover 9' held in position by means of the flanges on said cover 8'.
- The guide lever H' takes the form of a plate 115 which is slotted as indicated at 116 into which 5 slots depend the wire fingers 117.
- The wire fingers 117 extend downwardly, as indicated at 118, then upwardly as indicated at 119, to form a hump and finally downwardly as indicated at 120.
- 10 During normal operation, the fingers 117 and the plate 115 are so positioned that there will be recesses 114 formed between them through which the yarn F' passes.
- The lever 116 has a rear extension as indicated 15 at 29' in Figures 9 and 10 and is connected to the block 19' which is pivotally mounted at 15'.
- The extension 28' of the arm H' is clamped beneath the adjustable weight 128 which is held in position by means of the screw 129.
- 20 The block 19' during operation is normally balanced between the contacts 119 and 120, the contact 119 consisting of a nut which is screwed on to the end of the bolt 123, said bolt being insulated from the casing 10' by means of the 25 washers 125 and the sleeve 124.
- The contact 120 consists of the outstanding end of a closely wound coil spring 121, the lower end of which is held by the nut 119 under the washer 126 which also is connected to the end of the 30 electrical conduit 127.
- Excessive downward movement of the lever 116 causes its end portion 34' to contact with the end 35' of the block 36' which is pivotally mounted on the shaft 37'.
- 35 The block is provided with the upstanding element 38' having an eyelet 39' to which is connected the biasing spring 40'.
- The other end of the spring is connected to the flange 41' of the plate 43' which is pivotally 40 mounted at 46'.
- 40 The adjusting screw 47' provided with the handle 50'-51' is threaded through the block 49'.
- The motion of the block 36' is stopped by the adjustable screw or stop 53' provided with the 45 lock nut 56'.
- The lock nut 56' holds the upper ends 130 of the wires 117 rigidly in respect to the block 36'.
- In operation, the lever 116 may be readily depressed below the bottom of the return bend portions 118 to permit the yarn F' to be moved rearwardly until it contacts the downwardly extending portions 120 of the fingers 117.
- At this time, the lever 116 will be slightly above the dotted line position in Figure 9. Then the 55 lever 116 is permitted to move upwardly under the action of the spring 40' whereupon the yarn F' will be secured between the top of the hump 119 and the lever 116 in the space indicated at 114 of Figure 9.
- 60 During the operation, the yarn F' being in the position shown in Figure 9 in solid lines will prevent the lever 116 from elevating to such a position that the block 19' will contact the nut 119 and close the circuit through the conduit 127.
- 65 We note particularly by reference to Figure 10 that the yarn rests upon the upper surface of the lever H' with which it has three points of contact at 131 and below the humps 119 with which it has two points of contact indicated at 70 132.
- If, however, the yarn F' breaks or falls away from the stop mechanism of Figures 9 to 12, the lever 116 will elevate depressing the block 19' until it contacts the nut 119.
- 75 When the tension on the yarn is excessive due to tangling or because the yarn will not come off the cone or for other reasons, the lever 116 will be depressed into the dotted line position as indicated at Figure 9.
- At the same time, the portion 34' of the block 5 19' and 35' of the block 36' will contact which will result in movement of the wire fingers 117 into the dotted line position, as shown in Figure 9.
- This movement of the fingers 117 and particularly their lower portions 120 will result in the 10 yarn being forced off the fingers 116 and released.
- This will give an extra length of yarn for the machine to operate on during the time the stop motion mechanism is operating lessening the fall-outs and defects in the cloth being produced.
- During this depression of the lever 116', the block 19' will be elevated to contact the end 120 of the spring and cause a circuit through the conduit 127 and thereby stopping the mechanism. 20
- In case this contact does not take place sufficiently to assure this energization of the circuit 121, the lever 116 upon being released will immediately elevate under the ends of the adjustable weight 128 causing the block 19' to strike the 25 nut 119' and again establish the stopping circuit.
- Usually, however, there will be sufficient contact between the block 19' and the element 120 to cause such stoppage.
- The weight of the block 19' and of the adjusting member 128 are usually so regulated that the block 19' will bang against the nut 119 when released either due to breakage of yarn F' or due to removal of the yarn F' from the lever 116' as indicated in dotted line position in Figure 9. 30 35
- This will clear the nut 119 of any lint and will assure that proper contact take place to energize the circuit 127.
- The amount of movement of the fingers 117 and the point at which they are moved forward to 40 dotted line position by the lever 116 may be controlled by means of the stop screw 53'.
- The tension on the lever 116 may be regulated by adjustment of the angular position of the weight 128. The tension on the spring 40', resisting movement of the lever 116 from solid to dotted line position as indicated in Figure 9, may be adjusted by means of the threaded member 47'.
- 45 It will be noted in the present construction that the applicant eliminates the fixed guide G of Figures 1 to 8 with the result that the yarn F' only has to be threaded to start the machine upon a single lever H'.
- The operation of threading the yarn F' on the lever H' so that it gets beneath the humps 19 50 is relatively simple and may be readily performed by the operator of the knitting machine.
- It will be noted that the weight 128 of the block 19' of Figure 9 replaces the spring 57 of Figures 1 to 3; it is also possible, if desired, to 55 replace the other spring 40' by weight means, as indicated in my earlier applications, above referred to.
- If desired elements 117-118-119-120 may be fixed instead of movable by attaching these elements directly to the box 10' or by casting the elements 117 to 120 integrally with the box 10'; also the relative position of the elements 19' and 36' may be reversed with the element 36' being positioned above the element 19', the contact between the elements 19' and 36' being arranged at the other side of the fulcrum 15' with the pivots 15' and 37' being laterally disposed as indicated. 60
- 70 It is to be understood that many changes and 75

variations may be made in the present invention without departing from the essence or scope thereof and it is intended to include all such variations and modifications in the scope of the 5 appended claims.

What is claimed is:

1. In a stop motion mechanism for knitting machines, a base, means carried by said base to engage a rod extending outwardly from the head 10 of the machine, side wall members carried by said base, a plurality of shafts carried by said side wall members, a pivoted guide member connected to one shaft having an outstanding arm, the end of which is designed to receive the yarn 15 being fed to the machine, said shaft also receiving a movable contact element moving with said pivoted guide, a fixed contact element cooperating with said movable contact element, a take-up device attached to said second shaft, an adjustable spring resisting movement of said take-up device in one direction, and adjustable stop 20 limiting its movement in the other direction means to guide said yarn upon said lever, said lever being balanced by normal tension upon said 25 yarn to control said movable contact so that an electrical circuit will not be established in respect to said fixed contact, said take-up device and said adjustable spring resisting movement of said lever in the direction it tends to move under 30 excessive tension of the yarn.

2. A stop motion mechanism for knitting machines comprising a movable guide designed to be balanced in a predetermined position during normal operation of the machine by the yarn 35 passing thereover, a movable contact element, a fixed contact element, connections between said guide and said movable element to cause said movable element to move into contact with said fixed element upon movement of said guide away 40 from said predetermined balancing position and a looped lever cooperating with said movable guide provided with an extension to limit insertion of the yarn upon said guide, the loop of said lever serving to hold said yarn upon said guide 45 when said guide is in said normal balancing position.

3. A stop motion mechanism for knitting machines comprising a movable guide designed to be balanced in a predetermined position during normal operation of the machine by the yarn 50 passing thereover, a movable contact element, a fixed contact element, connections between said guide and said movable element to cause said movable element to move into contact with said

fixed element upon movement of said guide away from said predetermined balancing position and a looped lever cooperating with said movable guide provided with an extension to limit insertion of the yarn upon said guide, the loop of said lever serving to hold said yarn upon said guide when said guide is in said normal balancing position, said movable guide being slotted to receive said looped lever. 5

4. A stop motion mechanism for knitting machines comprising a movable guide designed to be balanced in a predetermined position during normal operation of the machine by the yarn passing thereover, a movable contact element, a fixed contact element, connections between said 10 guide and said movable element to cause said movable element to move into contact with said fixed element upon movement of said guide away from said predetermined balancing position and a looped lever cooperating with said movable 15 guide provided with an extension to limit insertion of the yarn upon said guide, the loop of said lever serving to hold said yarn upon said guide when said guide is in said normal balancing position, said movable guide consisting of a substantially horizontal blade provided with parallel 20 slots and said loop lever being provided with two parallel portions fitting in said slots. 25

5. A stop motion mechanism for knitting machines comprising a movable guide designed to be balanced in a predetermined position during normal operation of the machine by the yarn passing thereover, a movable contact element, a fixed contact element, connections between said 30 guide and said movable element to cause said movable element to move into contact with said fixed element upon movement of said guide away from said predetermined balancing position and a looped lever cooperating with said movable 35 guide provided with an extension to limit insertion of the yarn upon said guide, the loop of said lever serving to hold said yarn upon said guide when said guide is in said normal balancing position, said movable guide consisting of a plate having a plurality of slots therein over 40 which said plate the yarn passes and said looped lever consisting of a plurality of fingers received in slots in said plate, said looped lever being actuated by movement of said movable guide to lift said fingers out of said slots when said guide 45 is subjected to movement by excessive yarn tension. 50

JOE W. HAMILTON.
